The present design is an amusement game machine in which a player plays a game by operating a handle while viewing video and hearing sound; the front, left, and right displays are tilted forward so as to surround the player, making the player feel more present in the game. Fig. 1.8 is a center vertical cross-sectional view of Fig. 1.3 seen from the right with internal structure omitted; Fig. 1.9 is a center vertical cross-sectional view of Fig. 1.3 seen from the left with internal structure omitted; Fig. 1.10 is a center horizontal cross-sectional view of Fig. 1.3 seen from the top with internal structure omitted. For clarity of illustration, Fig. 1.11 is a front view with the seat removed, and Fig. 1.12 is a back view with the main body removed.

The long-dash-short-dash lines in the drawings denote boundaries of the claimed design and form no part thereof; the elements illustrated with oblique line shading are displays with reflective surfaces; the dash-dash broken lines depict environmental subject matter that forms no part of the claimed design.
